[57] CLAIM

The ornamental design for a toolboard, as shown and described.

DESCRIPTION

FIG. 1 is a front elevational view of the toolboard showing my new design;

FIG. 2 is a left side elevational view thereof, the undisclosed right side being a mirror image thereof;

FIG. 3 is a top plan view of the toolboard of FIG. 1; and,

FIG. 4 is a bottom plan view of the toolboard of FIG. 1. The undisclosed rear of the toolboard is flat and unornamented. The tools shown in broken lines are for illustrative purposes only and form no part of the claimed design.
